UNITED STATES PATENT OFFICE.

CHARLES J. SULLIVAN, OF SAN JOSE, CALIFORNIA.

ELECTRIC TIME-SWITCH.

SPECIFICATION forming part of Letters Patent No. 783,711, dated February 28, 1905.

Application filed October 10, 1904. Serial No. 227,811.

To all whom it may concern:

Be it known that I, CHARLES J. SULLIVAN, a citizen of the United States, residing at San Jose, Santa Clara county, State of California, have invented certain new and useful Improvements in Electric Time-Switches; and I do hereby declare the following to be a full, clear, and exact description of the same.

My invention relates to the class of time-controlled electric switches or circuit-breakers.

The object of my invention is to provide simple and effective means for turning on and off electric lights at predetermined times, to which end my invention consists in the novel construction, arrangement, and combinations of parts, which I shall now fully describe by reference to the accompanying drawings, in which —

Figure 1 is a front view of my time-switch. Fig. 2 is a top plan view of the same. Fig. 3 is an end view looking from the clock end of the device. Fig. 4 is an end view looking from the switch end. Fig. 5 is a detail showing the setting disks and dial. Fig. 6 is a face view of the dial, showing the arrangement of its figures. Fig. 7 is a detail plan view of the controlling devices of the crank 9. Fig. 8 is a detail of the back of the drop-arm guides, showing the cross-pin 21. Figs. 9 and 10 are details showing the two positions of the rock-arm 6 as controlled by the crank 9. Fig. 11 is a view, partly broken, of the top of one of the mercury-tubes 2.

1 is an electric switch or circuit-breaker. This may be of any suitable character adapted to close and open an electric circuit. The form here shown consists of mercury-containing tubes 2, suitably connected with the binding-posts 3 of the circuit. Into the mercury in the tubes the copper rods 4 are adapted to dip (through a suitable top guide, as seen in Fig. 11) to close the circuit, and said rods are adapted to be lifted from the mercury to open the circuit. The rods 4 are carried by a cross-head 5, which is itself carried upon one end of a rock-arm 6, pivoted to a bracket 7 and carrying a counterbalance-weight 8 at its other end. The rod-carrying end of the arm is the heavier, so that the rods dip into the mer-

cury by gravity, the weight 8 being only sufficient to prevent a too rapid descent of the rods, thereby avoiding splashing of the mercury.

The rock-arm 6 is controlled by a crank 9, which bears upon it between its fulcrum and weight, Figs. 2 and 4. The crank 9 is connected with a shaft 10, mounted in a frame 11, the axial rotation of said shaft being effected by a spring 12, acting through a gear-train 13, Figs. 1 and 7. The rotation of the shaft is controlled by a cross-arm 14 on its other end, which engages a catch 15. The engagement of the cross-arm with the catch is such as to permit said arm when released to have a half-revolution only, and the relative positions of said arm and the controlling-crank 9 are such that with each half-revolution of the arm the crank is turned alternately to its highest and lowest positions, as seen in Figs. 9 and 10. When at its highest position, the rock-arm 6 is allowed by gravity to swing up to it, so that the rods 4 of the circuit-breaker dip into the mercury and the circuit is closed. When, however, the crank 9 is at its lowest position, it presses down upon the rock-arm 6, and thereby lifts the rods 4 from the mercury and opens the circuit.

A suitable key 16, Fig. 1, is provided to wind up the spring 12 as required.

The catch 15 is a swinging catch pivoted in a bracket 17 and controlled by a spring 18. It is so arranged as to be withdrawn from under the end lug 19 of the arm 14 in order to trip said arm and to again protrude to catch the other end lug of said arm and limit the half-turn. The catch 15 has a stem 20, provided with a cross-pin 21, which when forced down causes the withdrawal of the catch to trip the arm.

The means for effecting the timely trip of said arm will now be described.

60 is a clock mechanism needing neither detailed description nor illustration. Upon its hour-hand sleeve 22 is a pinion 23, which meshes with a pinion 24 upon a shaft 25, Figs. 1 and 2, suitably mounted to rotate. Upon this shaft is a dial 26, properly inscribed to indicate time. Loosely mounted upon the shaft 25 and frictionally held to the hub of

the dial, as is shown in Figs. 1 and 5, is the setting-disk 27, which carries a pointer 28, projecting toward the dial to indicate the time set. This disk turns with the shaft and dial by reason of its frictional engagement, but is adapted to be independently rotated by hand in order to set its pointer to the proper time. The setting-disk 27 carries a cam 29 of a suitable character, here shown as a bent portion 15 of its periphery. The periphery of the disk plays in a forked extremity 30 of a lever 31, pivoted at 32, Fig. 2. The other extremity of this lever is provided or formed with two stops—one, 33, projecting beyond the other, 34, with a space between them, Figs. 2 and 3.

Pivoted at 35 to an upright 36 is a weighted drop-arm 37, the upper extremity 38 of which is a catch adapted to be engaged by the stops 33 and 34. The head of the drop-arm 37 20 plays in a guide 39, which directs it in falling down into contact with the cross-pin 21 of the stem 20 of the catch 15, heretofore described. The operation of these parts will now be understood. When at rest, the drop-arm 37 is held upright by its catch 38 resting on the outer stop 33 of the lever 31, Figs. 2 and 3; but when the cam 29 of the setting-disk 27 25 enters the forked end 30 of the lever 31 it swings said lever in such manner that the outer stop 33 of the lever moves from under the drop-arm catch 38, which immediately falls lightly upon the inner stop 34. As the cam advances through the forked end of the lever 31 the latter is swung back again, causing the stop 34 to remove from the drop-arm catch 38, and said drop-arm being now entirely 30 free drops down by gravity upon the cross-pin 21, and thereby releases the catch 15.

The resetting of the drop-arm 37 is automatic and is accomplished as follows: The arm 14, which is controlled by the catch 15, as heretofore described, has its ends provided with two lugs 19, Fig. 7, which project in a direction opposite to the direction of the lugs 19. 40 These lugs 19 lie in the path of movement of the drop-arm 37. The catch 38 of the drop-arm is a pivoted gravity-catch adapted to yield in passing up under the stop 33 and to return after passing said stop to engage it. Now, 45 as just stated, the lever 31 having been swung back to normal position in releasing the catch 38 of the drop-arm the outer stop 33 of said lever is thus in its first or normal position. The instant the drop-arm through contact with the cross-pin 21 effects the removal 50 of the catch 15 from the lug 19 of the arm 14, thereby permitting the half-revolution of said arm 14, said arm 14 in revolving brings one of its other end lugs, 19', up into contact with 55 the drop-arm 37 and throws said drop-arm up with sufficient force to cause it to reach its upper limit against a suitable head 40 of its guide. In reaching this limit its catch 38 passes by the outer stop 33 of the lever 31, 60 and the arm rebounding from the head 40 of

the guide the catch 38 comes to its first engagement with the outer stop 33.

If the setting-disk 27 be regarded as the one to close the circuit, there must now be described a second disk and mechanism to open the circuit. Mounted freely upon the shaft 25 and frictionally held to the other face of the hub of the dial 26 (which dial is to be inscribed on both faces) is a second setting-disk 41, having a pointer 42 and a cam 43. 75 The cam engages the forked end 44 of a second pivoted lever 45, the other end of which has two separated stops 46 and 47. These stops control a second drop-arm 48, provided with an upper catch 49 and directed in a second guide 50 to fall upon the cross-pin 21 of the catch 15. The lugs 19 of the arm 14 lie in the path of the second drop-arm and serve to throw it up again to reset it, as heretofore described in connection with the first drop-arm. 80

As the hour-hand sleeve of an ordinary clock revolves twice in twenty-four hours and as it is desirable to rotate the dial 26 but once in that time, I properly proportion the pinions 90 23 and 24 to this end. This further enables me to avoid any inaccuracy due to the inconvenience of seeing where to set the pointer if the hour wanted be at the time down in the lower and concealed part of the dial. As shown 95 in Fig. 6, I inscribe the face of the dial in duplicate in two semicircles of twelve hours, running from "1" to "12" in each division. In the setting-disks I fix a second pointer 61 diametrically opposite the first pointer. If, 100 therefore, the hour desired be down out of sight, I set the disk by the second pointer to the corresponding hour on the upper division, which is in plain sight, and thereby know that the first pointer is accurately set to the proper 105 hour below.

51 is a cushion for the end of the rock-arm 6.

In order to hold the device out of operation at or during any time desired, I have a catch 110 52, adapted to engage the end of the rock-arm 6 and hold it down permanently, thereby keeping the circuit open as long as desired. This position is shown in Fig. 4.

A description of the complete operation of the device will now be of service. 115

In the normal open-circuit condition of the apparatus the switch-rods 4 are held up out of the mercury by reason of the crank 9, which in its lowest position is held pressed down upon the rock-arm 6, as in Fig. 9. 120 In this position the cross-arm 14 is held by the catch 15, and the drop-arms 37 and 48 are held in an upright position. Suppose now that it be desired to close the circuit in order to start the lights at eight p. m. and that it be 125 desired to open the circuit in order to turn out the lights at five a. m. The disk 27 is turned to cause its pointer to indicate "eight p. m." on the dial 26, and the disk 41 is set to indicate the hour of "five a. m." The clock being 130

started, the cam 29 of disk 27 will enter the forked end of the lever 31 at eight p. m. The lever being thrown over and back again by said cam will release the drop-arm 37, which 5 striking the cross-pin 21 will withdraw the catch 15 from the lug 19 of the cross-arm 14. The cross-arm 14 being now released will, under the power of the spring 12, instantly commence its partial rotation. By this rotation 10 the crank 9 is turned to its upper limit, as in Fig. 10, thereby releasing the rock-arm 6, which will swing by gravity to dip the rods 4 into the mercury, thereby closing the circuit and starting the lights. The arm 14 has 15 meanwhile by one of its lugs 19' thrown the drop-arm 37 up again to its normal position with its catch 38 engaged by the stop 33 of the lever 31. Freed of the drop-arm the spring-controlled catch 15 has returned to 20 place in time to catch the opposite lug 19 of the arm 14, whereby said arm is limited at the end of the half-turn and held there, thus holding the crank 9 up and allowing the switch to remain closed. Thus the parts will remain 25 all night. At five a. m. the next morning the cam 43 of the disk 41 entering the forked end of lever 45 will swing said lever over and back, thereby releasing the drop-arm 48, which falling on the cross-pin 21 will withdraw the catch 15 from the lug 19 of the cross-arm 14. Said arm will thereupon rotate and carry the crank 9 down to its lowest position, which movement of the crank will press down 30 the rock-arm 6, thereby lifting the rods 4 from the mercury to open the circuit and put out the lights. Meanwhile the opposite lug 19 of the arm 14 has thrown the drop-arm 48 back again to its upright position, where it is held, and the catch 15 has caught and held the arm 40 14 at its half-turn. This is the position first assumed, and the apparatus is thus automatically reset and without further attention will operate again at the stated times. An eight-day clock may thus be employed, and 45 as long as the hours of operation remain the same the only attention required is to wind up the clock to wind up the spring 12 and to replenish the mercury as needed.

Having thus described my invention, what 50 I claim as new, and desire to secure by Letters Patent, is -

1. In an electric time-switch, the combination of a circuit-breaker, an arm for operating the same, a crank under normal rotary pressure for controlling said arm, a cross-arm for controlling said crank, a catch for holding and releasing said arm, and means for tripping said catch at predetermined times.

2. In an electric time-switch, the combination of a circuit-breaker, an arm for operating the same, a crank under normal rotary pressure for controlling said arm, a cross-arm for controlling said crank, a catch for holding and releasing said arm, a drop-arm for

tripping said catch, a stop for holding said drop-arm and means for disengaging said stop at predetermined times.

3. In an electric time-switch, the combination of a circuit-breaker, an arm for operating the same, a crank under normal rotary pressure for controlling said arm, a cross-arm for controlling said crank, a catch for holding and releasing said arm, a drop-arm for tripping said catch, a stop for holding said drop-arm, means for disengaging said stop at predetermined times, and means controlled by the cross-arm for throwing said drop-arm up to its stop again.

4. In an electric time-switch, the combination of a circuit-breaker, an arm for operating the same, a crank under normal rotary pressure for controlling said arm, a cross-arm for controlling said crank, a catch for holding and releasing said arm, a drop-arm for tripping said catch, a stop for holding said drop-arm, a pivoted lever for controlling said stop, a rotating cam for operating the lever, and means for setting the cam to predetermined times.

5. In an electric time-switch, the combination of a circuit-breaker, an arm for operating the same, a crank under normal rotary pressure for controlling said arm, a cross-arm for controlling said crank, a catch for holding and releasing said arm, a drop-arm for tripping said catch, a stop for holding said drop-arm, a pivoted lever for controlling said stop, a rotating cam for operating the lever, means for setting the cam to predetermined times, and means controlled by the cross-arm for throwing said drop-arm up to its stop again.

6. In an electric time-switch, the combination of a circuit-breaker, an arm for operating the same, a crank under normal rotary pressure for controlling said arm, a cross-arm for controlling said crank, a catch for holding and releasing said arm, a drop-arm for tripping said catch, a stop for holding said drop-arm, a pivoted lever for controlling said stop, a rotating cam for operating the lever, an adjustable setting-disk carrying said cam, a dial to govern the adjustment of said disk, a rotating shaft carrying the disk and dial, and a clock mechanism to drive the shaft.

7. In an electric time-switch, the combination of a circuit-breaker, an arm for operating the same, a crank under normal rotary pressure for controlling said arm, a cross-arm for controlling said crank, a catch for holding and releasing said arm, a drop-arm for tripping said catch, a stop for holding said drop-arm, a pivoted lever for controlling said stop, a rotating cam for operating the lever, an adjustable setting-disk carrying said cam, a dial to govern the adjustment of said disk, a rotating shaft carrying the disk and dial, a clock mechanism to drive the shaft, and means controlled

by the cross-arm for throwing said drop-arm up to its stop again.

8. In an electric time-switch, the combination of a circuit-breaker which includes vertically-movable contacts, a pivoted gravity rock-arm carrying said contacts, a crank bearing on said rock-arm and adapted by its rotation to permit and effect the rocking of said arm, a spring-controlled shaft carrying said crank and effecting its rotation, a cross-arm on said shaft, a catch for releasing the cross-arm and holding it again at a half-rotation, and means for tripping said catch at predetermined times.

15. 9. In an electric time-switch, the combination of a circuit-breaker which includes vertically-movable contacts, a pivoted gravity rock-arm carrying said contacts, a crank bearing on said rock-arm and adapted by its rotation to permit and effect the rocking of said arm, a spring-controlled shaft carrying said crank and effecting its rotation, a cross-arm on said shaft, a catch for releasing the cross-arm and holding it again at a half-rotation, a drop-arm for tripping said catch, a stop for holding said drop-arm and means for releasing the drop-arm at predetermined times.

10. In an electric time-switch, the combination of a circuit-breaker which includes vertically-movable contacts, a pivoted gravity rock-arm carrying said contacts, a crank bearing on said rock-arm and adapted by its rotation to permit and effect the rocking of said arm, a spring-controlled shaft carrying said crank and effecting its rotation, a cross-arm on said shaft, a catch for releasing the cross-arm and holding it again at a half-rotation, a drop-arm for tripping said catch, a stop for holding said drop-arm, means for releasing the drop-arm at predetermined times, and lugs on the cross-arm for throwing the drop-arm up to its stop again.

11. In an electric time-switch, and in combination with a circuit-breaker and means under normal rotary pressure for operating it, a cross-arm rotated by said means, said arm having laterally-extending lugs, a catch for controlling the rotation of said cross-arm and limiting it to a half-revolution, a drop-arm adapted to trip said catch, said arm playing in the path of the lugs of the cross-arm whereby the drop-arm is thrown up again to its first position, a stop to hold said drop-arm up, and means for disengaging said stop at predetermined times.

12. In an electric time-switch, and in combination with a circuit-breaker and means for operating it which include a rotatable cross-arm and a catch for controlling said arm, a drop-arm for tripping said catch, means on the cross-arm for throwing said drop-arm up to normal position, a pivoted lever having on its extremity the outer and inner separated stops for engaging and releasing said drop-arm, and

means for swinging said lever at predetermined times to release and reengage the drop-arm.

13. In an electric time-switch, and in combination with a circuit-breaker and means for operating it which include a rotatable cross-arm and a catch for controlling said arm, a drop-arm for tripping said catch, means on the cross-arm for throwing said drop-arm up to normal position, a pivoted lever having on its extremity the outer and inner separated stops for engaging and releasing said drop-arm, said lever having a forked opposite end, a setting-disk having a cam playing in the forked end of the lever to swing it, a dial by which the disk is set to predetermined times, a shaft carrying the disk and dial, and a clock mechanism to drive the shaft.

14. In an electric time-switch, the combination of a circuit-breaker, means under normal rotary pressure for operating it, a cross-arm controlling said means, a catch controlling said arm, a pair of drop-arms for independently releasing the catch, stops for independently holding and releasing said arms, and means independently adjustable for separately releasing said stops to drop the arms independently at predetermined separate times.

15. In an electric time-switch, the combination of a circuit-breaker, means under normal rotary pressure for operating it, a cross-arm controlling said means, a catch controlling said arm, a pair of drop-arms for independently releasing the catch, stops for independently holding and releasing said arms, and means independently adjustable for separately releasing said stops to drop the arms independently at predetermined separate times comprising separate levers, setting-disks independently adjustable, a cam on each disk to operate said levers, a dial to which said disks are adjusted from opposite sides, a shaft carrying the disks and dial, and a clock mechanism to drive the shaft.

16. In an electric time-switch, the combination of a circuit-breaker, means under normal rotary pressure for operating it, a cross-arm controlling said means, a catch controlling said arm, a pair of drop-arms for independently releasing the catch, stops for independently holding and releasing said arms, lugs on the cross-arm for throwing said drop-arms up again to their stops, and means independently adjustable for separately releasing said stops to drop the arms independently at predetermined separate times.

17. In an electric time-switch, the combination of a circuit-breaker, means under normal rotary pressure for operating it, a cross-arm controlling said means, a catch controlling said arm, a pair of drop-arms for independently releasing the catch, stops for independently holding and releasing said arms, lugs on the cross-arm for throwing said drop-arms

up again to their stops, and means independently adjustable for separately releasing said stops to drop the arms independently at predetermined separate times comprising separate levers, setting-disks independently adjustable, a cam on each disk to operate said levers, a dial to which said disks are adjusted from opposite sides, a shaft carrying the disks

and dial, and a clock mechanism to drive the shaft.

In witness whereof I have hereunto set my hand.

CHARLES J. SULLIVAN.
